UNITED STATES PATENT OFFICE.

CHARLES W. WRIGHT, OF BLOOMINGTON, ILLINOIS.

REBORING DEVICE.

Application filed September 23, 1924. Serial No. 739,393.

The object of my said invention is the provision of a practically advantageous device designed more especially for reboring the cylinders of automobile engines of the 5 internal combustion type.

To the attainment of the foregoing, the invention consists in the improvement as hereinafter described and definitely claimed.

In the accompanying drawings, forming 10 part of this specification:—

Figure 1 is a side elevation showing the preferred embodiment of my invention equipped to be actuated by a motor.

Figures 2, 3 and 4 are cross-sections taken 15 in the planes indicated by the lines 2—2, 3—3 and 4—4, respectively, of Figure 1.

Figure 5 is a diametrical section of the device taken on the line 5—5 of Figure 4.

Figure 6 is a diametrical section taken 20 on the line 6—6 of Figure 4.

Figure 7 is a detail plan view partly in section of the nut for positioning the knife blades of the device relative to the center thereof and when blades of different sizes 25 are to be used.

Figure 8 is a detail view of one of the interior nuts of the device.

Figure 9 is a detail view of one of the 30 knife blades.

Similar numerals of reference designate corresponding parts in all of the views of the drawings.

Among other elements my novel device 35 comprises a head 1 having a central aperture 2 and also having threaded bores 3 extending to its sides.

When my novel device is to be driven or turned about its axis by a motor, a yoke 4 such as shown in Figures 1 and 2 is connected by bolts 5 through the head 1, the 40 said yoke having a shank 6 for connection to a motor or for connection to a drill or the like driven by a motor. When, however, my novel device is to be operated by hand the yoke 4 is removed as are also the bolts 5 and handles 7 such as shown in Figure 7 45 are threadedly fixed in the head 1.

The head 1 is superimposed on and connected by screws 8 or other appropriate 50 means to the upper end of a body 9, and it will also be noted by a reference to Figure 5 that I prefer to employ pins 10 for correctly positioning the head 1 on the body 9.

A shaft 11 extends through the head 1 55 and body 9 and is enlarged at 12 and is provided with a thread 13.

The upper portion of the body 9 is reduced and exteriorly threaded as designated by 14, and the said body 9 is exteriorly shouldered as designated by 15. The body 60 portion 14 is for the engagement of a nut 16, the said nut having an apertured portion 17 for the engagement of a spanner and also having a circumferential base flange 18. The shoulder 15 of the body 9 is for the support of the stop plate 19, the said plate 65 19 being connected to the body 9 through the medium of screws 20, Figures 3 and 5.

Interiorly the body 9 is provided in its lower portion with a comparatively large bore 21 in which are disposed a slide member 22, and a nut 23 in engagement with the thread 13. A coiled spring 24 surrounds the shaft 11 and is interposed between and bears against the opposed ends of the member 22 and nut 23. This spring 24, I term 70 a "kick back" spring inasmuch as it serves to push the slide member 22 back to release the top set of lugs hereinafter described when the device is being removed from a cylinder. An expansion spring 24^x is partially housed in the slide member 22 and is interposed between said slide member and an abutment 10^x on the shaft 11. This expansion spring assures even pressure on the 75 lugs hereinafter described and maintains an accurate center at all times. The said nut 23 is held against turning in the body 9 by a pin 25 on the nut disposed in a longitudinal guideway 26 in the body 9. It 80 will also be noticed that the member 22 and nut 23 are provided with taper portions 27. These taper portions bear against the beveled inner ends of lugs 28, Figure 6, 85 guided in the body 9 and yieldingly pressed inward or toward the axis of the body 9 by springs 29, Figures 1 and 6. The said lugs 28 by engaging the wall of a cylinder bore 90 serve to regulate the depth of the cut, and in virtue of the said lugs 28 being adjustable 100 they are adapted to be used in conjunction with cutting blades 30 of different sizes.

Any desired number of cutting blades 30 may be employed in the device at one and 105 the same time, though I would have it understood that I prefer to employ six blades as made clear by Figure 4. I would also have it understood that the blades 30 may be of different sizes, my improvement 110 providing for the ready removal of one set of blades and the incorporation of another set of blades. This will be better understood

when it is stated that the blades 30 are provided at opposite ends with hooks 31 and that the blades are maintained in working position by upper and lower spring rings 32 which encompass the upper and lower ends of the blades and serve to yieldingly hold the same against outward radial movement.

The body 9 is provided at its outer side 10 with tapers 33, and the blades 30 are provided with the inclined inner edges 34 and 35 to engage said tapers; and it will also be noticed that the blades are shouldered at 36 to bring up against the shoulder 37 of 15 the body 9 so as to limit upward movement of the blades as shown in Figure 5. It will also be noticed by reference to Figure 5 that the blades 30 are notched at 38 to receive the flange 18 of the nut 16 and that the blades 20 extend above and below the stop plate 19 which is adapted to rest on the upper end of a cylinder that is to be reborbed and support the reborbing device while at work.

Manifestly by applying appropriate 25 means to the upper end of the shaft 11 the said shaft 11 may be conveniently turned about its axis for the convenient adjustment of the device.

It will be apparent from the foregoing 30 that by adjusting the nut 16 the blades 30 may be made to extend to a greater or less extent radially from the body, and by turning the shaft 11 the lugs 28 may be thrust to a greater or less extent laterally from the 35 body, the springs 29 serving at all times to yieldingly hold the lugs 28 in engagement with the member 22 and nut 23.

I have specifically described the construction and relative arrangement of the parts 40 comprised in the preferred embodiment of my invention in order to impart an exact understanding of said embodiment. I do not desire, however, to be understood as confining myself to the specific construction 45 and relative arrangement of parts as disclosed inasmuch as my invention is defined by my appended claims within the scope of which changes may be made without affect-

ing or involving departure from my invention.

Having described my invention, what I claim and desire to secure by Letters-Patent, is:—

1. A reborbing device comprising a body having a bore, means connected to said body for the turning of the same about its axis, a threaded shaft extending through the body, a nut disposed and held against turning in the body and engaged by the body and having a tapered portion, a slide member on the shaft having a tapered portion, a spring between the nut and said slide member, an expansion spring between said member and an abutment on the shaft, lugs guided in the body and disposed against said tapered portions of said nut and slide member whereby movement of the nut and slide member on the shaft will adjust said lugs transversely of the body, and cutting blades supported upon the body.

2. A reborbing device comprising a body having a bore, means connected to said body for the turning of the same about its axis, a threaded shaft extending through and adapted to abut against said body, a nut disposed and held against turning in the body and engaged by the thread of said shaft and having a tapered portion, a slide member on the shaft and having a tapered portion, a spring between the nut and said slide member, an expansion spring between said slide member and an abutment on the shaft, lugs guided in the body and disposed against the tapered portions of the nut and slide member whereby movement of the nut and slide member on the shaft will adjust said lugs transversely of the body, cutting blades supported upon the body, the said body having a shoulder at the intermediate portion of its length and being combined with a stop plate superimposed on and connected to the same and adapted to rest on a cylinder for supporting the device in the bore of the cylinder.

In testimony whereof I affix my signature.
CHARLES W. WRIGHT.
